UNITED STATES PATENT OFFICE

GROSVENOR N. ALLEN, MARY G. PARKER, AND LLOYD E. RESSEGGER, OF ONEIDA, NEW YORK, ASSIGNORS TO ONEIDA COMMUNITY, LIMITED, OF ONEIDA, NEW YORK, A CORPORATION OF NEW YORK

DESIGN FOR A SPOON OR SIMILAR ARTICLE

Application filed February 10, 1932. Serial No. 42,809. Term of patent 14 years.

To all whom it may concern:

Be it known that we, GROSVENOR N. ALLEN, MARY G. PARKER, and LLOYD E. RESSEGGER, citizens of the United States, residing at Oneida, county of Madison, and State of New York, have invented a new, original, and ornamental Design for a Spoon or Similar Article, fully described and represented in the following specification and the accompanying drawing, forming a part of the same, in which—

Figure 1 is a front elevation of a spoon or similar article, showing our new design;

Figure 2 is a fragmentary view showing the handle in reverse elevation; and

Figure 3 is a longitudinal sectional view on line 3—3 of Fig. 1.

The essential feature of our new design is the ornamentation on the front face of the spoon or similar article.

We claim:

The ornamental design for a spoon or similar article as shown and described.

In testimony whereof we have hereunto set our hands.

GROSVENOR N. ALLEN.
MARY G. PARKER.
LLOYD E. RESSEGGER.
